UNITED STATES PATENT OFFICE

TALMON A. DAVENPORT, OF DETROIT, MICHIGAN, ASSIGNOR TO BUDD WHEEL COMPANY, OF PHILADELPHIA, PENNSYLVANIA, A CORPORATION OF PENNSYLVANIA

DESIGN FOR A WHEEL

Application filed March 17, 1931. Serial No. 39,120. Term of patent 14 years.

To all whom it may concern:

Be it known that I, TALMON A. DAVENPORT, a citizen of the United States, residing at Detroit, Wayne County, Michigan, have invented a new, original, and ornamental Design for Wheel, of which the following is a specification, reference being had to the accompanying drawings, which forms a part thereof.

Figure 1 is an elevational view of a wheel showing my new design.

Figure 2 is a central axial section of my wheel in diagrammatic outline.

The salient feature of my invention is the provision, in the body portion of a vehicle wheel, of alternate oppositely arranged openings, the metal between them simulating, in appearance, diverging rounded spokes of substantial proportions.

I claim:

The ornamental design for a wheel as shown and described.

Signed at Detroit, Wayne County, Michigan, this 30th day of September 1931.

TALMON A. DAVENPORT.
